C. E. DODSON

VANITY BOX

Filed July 2, 1923

Inventor,
Carroll E. Dodson

Witness:

R. E. Hamilton

UNITED STATES PATENT OFFICE.

CARROLL E. DODSON, OF KANSAS CITY, MISSOURI.

VANITY BOX.

Application filed July 2, 1923. Serial No. 648,383.

To all whom it may concern:

Be it known that I, CARROLL E. DODSON, a citizen of the United States, residing at Kansas City, in the county of Jackson and State of Missouri, have invented a certain new and useful Improvement in Vanity Boxes, of which the following is a complete specification.

This invention relates to vanity boxes of 10 that class wherein face powder is pressed against a permeable or reticulated surface, for accessibility by a powder puff, and my prime object is to provide for use within a conventional case, a package for loose powder and means for feeding the contents of 15 the package to the said surface element of the package.

Another object is to produce a package which can be loaded by the user as necessity 20 arises, at minimum expense, and in which the full charge is available for use.

With these objects in view, the invention consists in certain novel and useful features of construction and organization of parts as 25 hereinabove described and claimed; and in order that it may be fully understood, reference is to be had to the accompanying drawing, in which:

Figure 1 is a perspective view of a vanity 30 box in open condition and equipped with a powder container or package embodying the invention, the customary "puff" being shown in detail.

Figure 2 is an enlarged central vertical 35 section taken through the vanity box in closed position.

Figure 3 is a top plan view of the box, as shown in Figure 1, but with the powder 40 container removed to show the automatic feeder element on the bottom of the box.

Figure 4 is a top plan view of the powder 45 container.

In the said drawing where like reference characters identify corresponding parts, 1 indicates a suitable cylindrical box reduced 45 at its upper edge at 2, to produce internal downwardly-facing and external upwardly-facing shoulders 3 and 4 respectively.

Adapted to embrace the portion 2 and 50 rest on the shoulder 4, and having a hinge connection 5 with the box, is a lid or top member 6, provided with a suitable mirror 7 on its inner face. The construction thus far described is of common and well known 55 type and it is believed unnecessary to make any further detail reference thereto.

Adapted to rest on the bottom of the box 1 and having frictional engagement with the wall thereof is a spider 8 which carries in alignment with the axis of the box, a suitable expansion spring 9 which is adapted to automatically feed the powder upward as will hereinafter appear.

The powder container is constructed as follows; 10 indicates a circular disc or bottom of cardboard or other suitable material, inclosed by a circular wall or band 11, formed at its lower end with an inwardly-projecting circumferential flange 12 upon which the bottom 10 is adapted to rest when the box is fully charged with powder P, in loose condition.

A relatively V-shaped ring 13 is adapted to have frictional engagement with the upper edge of the wall, and clamped between said wall and ring and tightly stretched across the open end of the former, is a suitable permeable or reticulated fabric or metallic screen 14.

The tendency of the spring 9 is to force 80 the bottom 10 upwardly and push the powder against and through the screen 14, and in order to prevent undue upward movement of the powder container and also to hold the parts in position when the box is turned upside-down, the ring 13, is provided at diametrically opposite points with a pair of downwardly-projecting flanges 15, turned slightly outward at their lower ends and being adapted to be engaged under the inside shoulder 3 of the box 1, as will be 85 readily understood.

Fitted within the box and resting on the screen is a suitable powder puff 16, it being apparent that by slightly pressing the puff 90 against the screen and sliding it thereon, a quantity of powder will be taken up by and deposited on the puff.

As the powder is consumed, as above 95 mentioned, the spring 9 will force the false bottom 10 upwardly and maintain the powder in yielding relation to the screen until it has all been consumed.

The powder container may then be removed from position and recharged as will 100 be readily understood.

From the above description, it will be apparent that I have produced a device of the character described which possesses the features of advantage set forth as desirable; and while I have described and claimed the preferred embodiment of the same,

the right is reserved to make all changes properly falling within the spirit and scope of the appended claims.

I claim:

5. A vanity box, a powder container in said box, comprising a wall having its lower edge inturned, a follower bottom resting on said inturned edge, a screen closing the upper end of said wall, a clamp ring encircling the upper edge of the wall and clamping said screen in position.

2. A vanity box, a powder container in said box, comprising a wall having its lower edge inturned, a follower bottom resting 15 on said inturned edge, a screen closing the upper end of said wall, a clamp ring encircling the upper edge of the wall and

clamping said screen in position, a spring in said box for yieldingly advancing said bottom.

3. A vanity box, a powder container in said box, comprising a wall having a movable bottom, a screen closing the upper end of said wall, a clamp ring encircling the upper edge of the wall and clamping the screen 25 in position, a spring in said box for yieldingly advancing said bottom, and a pair of ears on said ring for interlocking engagement with said box to prevent accidental upward movement of the container.

In testimony whereof, I have hereunto set my signature.

CARROLL E. DODSON.
